US00D473861S

(12) **United States Design Patent** (10) Patent No.: **US D473,861 S**
Stanton et al. (45) Date of Patent: ** *Apr. 29, 2003

(54) **INTERFACE DEVICE**

D355,897 S * 2/1995 Nakanishi et al. D14/373

(75) Inventors: **James M. Stanton**, San Jose, CA (US);
Kuni Masuda, Cupertino, CA (US);
Howard M. Stoltz, Soquel, CA (US);
Craig M. Leverault, Mountain View,
CA (US); **Michael S. Dann**, Palo Alto,
CA (US)

* cited by examiner

(73) Assignee: **Sun Microsystems, Inc.**, Palo Alto, CA
(US)

Primary Examiner—Freda Nunn
(74) Attorney, Agent, or Firm—O'Melveny & Myers LLP

(*) Notice: This patent is subject to a terminal disclaimer.

(57) **CLAIM**

The ornamental design for an interface device, as shown and described.

DESCRIPTION

(21) Appl. No.: **29/139,864**
(22) Filed: **Apr. 5, 2001**
(51) LOC (7) Cl. **14-02**
(52) U.S. Cl. **D14/337**
(58) Field of Search D14/336, 337,
D14/371, 373, 388, 125-129; 345/104,
156, 168, 173; 348/180, 184, 325, 739;
341/12; 349/1, 2, 11, 62; D18/4.5

FIG. 1 is a front and right side perspective view of an interface device;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a front elevational view of a second embodiment thereof; and,

FIG. 9 is a rear elevational view thereof showing vents.

(56) **References Cited**

FIG. 1 is a front and right side perspective view of an interface device;
